UNITED STATES PATENT OFFICE.

CHARLES D. WINTERS, OF ASBURY PARK, NEW JERSEY, ASSIGNOR OF ONE-HALF TO CHARLES G. STOCKTON, OF OCEAN GROVE, NEW JERSEY.

ADVERTISING DISPLAY SIGN.

Application filed February 23, 1924. Serial No. 694,634.

This invention relates to changing electric signs, though it is noted that the invention is not limited to changing signs or electric signs, nor in some respects even to luminous signs.

One object of the invention is to provide an apparatus or device of this kind in which the letters and characters of the sign may be easily interchanged for displaying a variety of matter.

Another object of the invention is to provide an apparatus or device of this kind having efficient means for instantaneously changing the sign to present the successive parts of sentences or other matter.

Another object of the invention is to provide an apparatus or device of this kind having an improved means of mounting sign illuminating means and means for darkening the sign during the changes.

Another object of the invention is to provide an apparatus or device of this kind having fixed, or constant, signs associated with the variable or changing sign and forming to or completing or forming a continuation of the variable sign.

Other objects of the invention are to improve generally the simplicity and efficiency of such devices and to provide a device or apparatus of this class which is durable, economical to manufacture and operate and which will not get out of order.

Still other objects of the invention will appear as the description proceeds; and while herein details of the invention are described, the invention is not limited to these since many and various changes may be made without departing from the scope of the invention as claimed.

The inventive features for the accomplishment of these and other objects are shown herein in connection with an improved sign which, briefly stated, includes a motor driven rotary drum mounted between two supporting brackets and provided with removable sides each provided with a row of letter openings in which are seated individual letter or character frames secured by latches and formed with panels having the characters perforated therein. A housing over the drum is provided with a window through which the rows of characters are successively exposed as the drum is rotated

step by step by a suitable motor driven means which also, as the drum moves a step, cuts off current from electric lamps carried in a reflector inside of the drum.

In the accompanying drawing, showing by way of example, one of many possible embodiments of the invention.

Fig. 1 is a fragmental front elevation, partly in section, showing the apparatus;

Fig. 2 is an end elevation partly in section showing the drum and its rotating mechanism;

Fig. 3 is an elevation showing the opposite end of the drum and the motor for driving the same;

Fig. 4 is a longitudinal vertical sectional view, partly in elevation, showing one of the brackets supporting the drum;

Fig. 5 is a transverse vertical sectional view, partly in elevation, showing the reflector and a lamp therein;

Fig. 6 is a fragmental front elevation showing a removable side and removable letter frame seated therein;

Fig. 7 is a transverse vertical sectional view, taken on the line 7-7 of Fig. 6, looking in the direction of the arrow of said line;

Fig. 8 is a transverse vertical sectional view, taken on the line 8-8 of Fig. 6, looking in the direction of the arrow of said line;

Fig. 9 is a front elevation showing a letter frame;

Fig. 10 is a transverse vertical sectional view of a letter frame with the latch open;

Fig. 11 is an enlarged transverse vertical sectional view, partly in elevation, showing the frame in the letter opening with the latch open;

Fig. 12 is a similar vertical sectional view, with the latch closed;

Fig. 13 is a front elevation of another form of a sign;

Fig. 14 is a fragmental side view of the gear and contact plate thereon shown in front elevation in Fig. 1; and

Fig. 15 is a diagram of the electric circuit appurtenant to said gear and contact plate.

The various parts of the apparatus are carried on a base 10 carrying upright brackets 11 and 12 provided with aligned bores re-

ceiving outer bushings 13 and 14 fitted in said bores in turn receiving inner bushings 15 (Figs. 1 and 4), each having an inner flange 16 spaced from the outer bushing. 5 The bushings are held in place by set screws 17 and 18.

Between said brackets is mounted a rotary drum 20 including a frame comprising heads 21 provided with bores 22 received on said 10 outer bushings 13. Horizontal rods 25 (Fig. 3) connect said heads and carry a plurality of sides 26 covering said frame and provided with intermeshed inwardly curved edge flanges 27 (Fig. 7) clasping partly around 15 said rods. Each of said sides is provided with a row of letter openings 28; and a housing 30 (Figs. 1 and 2) disposed over said drum is provided with a window 31 with which the front row of openings registers. 20

Individual letter or character frames 35 interchangeably seated in the letter openings, each comprises an outer flange 36 (Fig. 11) adapted to rest flat against the outer 25 face of said sides 26, and an impressed panel 37 perforated with letters or other characters 38 (Fig. 9). The impressing of said panel forms an inwardly beveled marginal portion 40 adapted to seat in said letter 30 openings 28 (Fig. 11).

Said marginal portions 40 are provided with upper and lower apertures 41 receiving oppositely projecting ends 42 of a latch 43 having a bail portion 44 adapted to be disposed forwardly of the letter opening 28 (Fig. 4) or to be caught under a projection 45 (Fig. 6) in said marginal portion 40. Said opposite ends 42 are disposed at right angles to the ends 47 of the bail portions 40 and inclined away from the plane of the bail portion on the same side of said plane as shown in Fig. 7. Thus when the bail portion is disposed straight in front of the letter opening the ends 42 are removed from 45 the inner face of said sides 26 (Fig. 11) but when the bail portion is caught under said projection 45 (Fig. 12) said ends 42 are engaged tightly against said inner face to hold the letter frames 35 securely in place. 50 Thus the frames are easily interchanged for spelling different combinations.

A reflector 50 (Fig. 4) having an open front towards the front row of openings 28 is provided in its end walls with central 55 openings 51 received on said inner bushings 15 between the flanges 16 thereof and the outer bushings 13. Lamps 52 are mounted in sockets 53 (Fig. 5) in the rear of the reflector whereby the perforations of the 60 characters are illuminated.

A motor bracket 54 (Figs. 1 and 3) adjacent to said bracket 12 carries a motor 55 provided on the lower end of its shaft with a beveled gear 56 meshing with a pinion 57 fast on a governor shaft 58 mounted in said

motor bracket and carrying a governor 59 and a worm 60. A reducing gear shaft 64 mounted in said motor and reducing gear brackets is provided at one end with a worm wheel 65 engaging said worm 60 and at the other end with a small pinion 66 meshing with a large contact gear 67 (Fig. 2) provided with an arcuate contact face 68 of less than 180°. Said gear is mounted on a stub shaft 69 rotatably mounted in the gear 75 bracket provided at the inner end with a disk 70 (Fig. 1) carrying a crank 71.

An insulating block 73 mounted upon said gear bracket 63 carries a pair of separated contact brushes 74 mounted on said block 80 adapted simultaneously to engage and disengage contact face 68 as the reducing gear rotates. Line conductors 75 (Fig. 15) extending to said motor feed current to service conductors 76 and 77 connecting said brushes and said lamp sockets in series across said line conductors and passing through said inner bushings 15 and a rear bushing 78 in the rear wall of the reflector.

A rocking arm 80 (Fig. 2) is mounted on 90 said outer bushing 13 and is retained by a flange 81 and connected to a link 82 connecting the outer end of the arm with said crank 71. A spring pawl 83 (Fig. 2) on said arm presses against the adjacent head 21 and is engageable with pins 84 carried on said head, whereby as said contact gear rotates, said frame brings another row of letter openings in front of the sign window. Said contact face and said arm are so related 100 that the current is broken and the lights are out as the drum moves a step. An extension bracket 85 mounted on the upright bracket 12 carries a friction pad 86 engaging the head 21 opposite to the first to control 105 the momentum or throw of the drum in its rotation when the drum is moved step by step by engagement of the pawl 83 with the pins 84.

The operation is simple, and obvious from 110 the foregoing. The housing 30 being removed, the frames 35 are selected to spell the required words and placed in the openings 28. To insert the frame, the latch is moved to the position of Fig. 10, the lower 115 end 42 is placed through the opening 28 and the frame slightly lowered to permit the upper end 42 to be passed through the opening. The frame is then seated and the latch moved to the position of Figs. 6 and 120 12 to lock the frame in place.

The housing is then replaced and the current turned on, thus causing the lamps to light, the crank 71 to revolve, the pawl to oscillate and the drum to rotate step by step, 125 thus successively to register the rows of characters with the window 31 to expose the sign.

The contact face 68 engages the brushes to light the lamp on the back stroke of the 130

pawl while the drum is stationary, and is disengaged from the brushes during the active stroke of the pawl while the drum is moving and one line of characters is being exchanged for another.

Obviously, the signs may be made of any size and shape required for interior or exterior use, and the axis need not be horizontal or longer than the diameter of the drum. Neither is it necessary that the signs be illuminated by interior means, or at all when used during the day. The sign of Fig. 1 thus may be used either as an illuminated sign or a day sign.

Neither is it necessary that all of the signs be illuminated or all changing. The roof sign 90 shown in Fig. 13 mounted on a building 91 includes a rotary drum similar to that of Fig. 1 and having rows of characters thereon to provide a changing sign 92. A housing secured over said drum is provided in its front wall 93 with a horizontal sign window 94 with which the front row of said characters registers. Illuminated or unilluminated constant signs 95 and 96 disposed in said front wall are associated with and form a part or continuation of said changing sign. Thus the fixed and changing signs cooperate to form a complete sign, though the invention is not limited to signs relating to a single subject.

I claim:

1. In combination, a rotary drum having a plurality of removable sides having each a row of openings therein; individual character frames removably seated in said openings; a wall having a window in front of a row of said frames; and means for rotating said drum.

2. In combination, a rotary drum having a plurality of removable sides each side having a row of aligned openings therein; individual frames removably secured in said openings and provided with translucent display characters; a housing around the drum having a sight opening with which the frames secured in said openings are successively registerable when the drum is rotated; means for illuminating the translucent characters when the frames are in registration with said sight opening; and means for rotating the drum step by step.

3. In combination, a rotary drum having a plurality of removable sides each side having a row of aligned openings therein; individual frames removably secured in said openings and constituting a plurality of rows of frames corresponding to said rows of openings and provided with translucent display characters; a housing around the drum having a sight opening with which the rows of frames secured in said openings are successively registerable when the drum is rotated; means for rotating the drum step by step;

means for illuminating the translucent characters; and means for lighting said means for illumination when one of the rows of frames is in registration with said sight opening and extinguishing said means for illumination when all the rows of frames are out of registration with the sight opening.

4. In combination, a drum comprising a frame having heads and horizontal rods connecting said heads, and a plurality of sides covering said frame and provided with intermeshed inwardly curved edge flanges clasping partly around said rods, said sides being provided with rows of letter openings; individual character frames removably seated in said openings and having characters perforated therein; a light in said drum; and means for rotating said drum.

5. In combination, upright brackets provided with aligned bores; outer bushings fitted in said bores; inner bushings fitted in said outer bushings, each having an inner flange spaced from the outer bushing; a drum comprising heads rotatably mounted and rotatably received on said outer bushings; sides connecting said heads; said sides being provided with rows of translucent characters; a wall having a window with which the front row of said translucent characters registers; a reflector having an open front towards said front row and provided in its end walls with openings and received on said inner bushings between the flanges thereof and the outer bushings; lamps mounted in the rear part of said reflector; conductors passing through said inner bushings and leading to said lamps; and means for rotating said drum step by step.

6. In combination, uprights carrying bushings; a drum rotatably carried on the bushings and having rows of translucent characters thereon; a reflector secured on said bushings; a light in the reflector; and means for rotating the drum.

7. In combination, upright brackets provided with aligned bores; outer bushings fitted in said bores; inner bushings fitted in said outer bushings, each having an inner flange spaced from the outer bushing; a frame comprising heads provided with bores received on said outer bushings, and horizontal rods connecting said heads; a plurality of sides covering said frame and provided with intermeshed inwardly curved edge flanges clasping partly around said rods; said sides being provided with rows of letter openings; a housing over said frame provided with a window with which the front row of letter openings registers; individual character frames removably seated in said openings; electric lights in said drum; conductors passing through the inner

4

bushings to the lights; and means for rotating said drum step by step and darkening said lights.

8. In combination, a rotary drum having a plurality of sides having openings therein; a housing over said frame provided with a window with which the front row of openings registers; individual letter or character frames for the letter openings, each comprising an outer flange adapted to rest against the outer face of said sides and an impressed panel perforated with said letter characters and forming an inwardly beveled marginal portion adapted to seat in said letter openings; said marginal portions being provided with upper and lower apertures and at one side with an outpressed projection; a latch comprising a pair of oppositely projecting ends engaged through said perforations and extended behind said sides, and a bail adapted to be disposed forwardly of the letter opening or to be caught under said projection.

9. In combination, a compartment comprising a side provided with a row of letter openings; individual letter or character frames each having an impressed panel for seating in the letter openings and having a character thereon; and latches comprising a bail portion in front of the panel and ends engaging behind the margins of said openings to hold the letter frames in place.

10. In combination, a compartment having a plurality of sides having letter openings therein; individual letter or character frames for the letter openings, each frame comprising an outer flange adapted to rest against the outer face of said sides and an impressed panel perforated with said letter characters and forming an inwardly beveled marginal portion adapted to seat in said letter openings; said marginal portions being provided with upper and lower apertures and at one side with an outpressed projection; and a latch comprising a pair of oppositely projecting ends engaged through said perforations, and a bail adapted to be disposed forwardly of the letter opening or to be caught under said projection; said opposite ends being disposed at right angles to the ends of the bail portion and inclined away from the plane of the bail portion on the same side of said plane whereby when the bail portion is disposed straight in front of the letter openings the said ends are removed from the inner face of said sides, and whereby when the bail portion is caught under said projection, said ends are engaged tightly against said inner face to hold the letter frames in place.

11. In combination, opposed upright brackets; a rotary drum having heads and a plurality of sides having letter openings therein; a housing around said drum having a window; individual character frames

removably seated in said openings; a reducing gear bracket adjacent to one of the opposed upright brackets; a drive shaft mounted in said reducing gear bracket and provided at its end with a small pinion; a stub shaft rotatably mounted in the gear bracket provided at the inner end with a crank and at the outer end with a large gear meshing with said pinion; a rocking arm pivoted coaxial with said drum; a link connecting the outer end of said arm with said crank; a spring pawl on said arm pressing against the adjacent head; and pins carried on the adjacent head and engaged by said pawl whereby as said contact gear rotates said frame brings successive rows of letter openings in front of said window.

12. In an advertising display device, in combination, a rotatable drum; means for rotating the drum; means cooperating with said means for rotating and including spring means engaging pin means on one head of the drum for providing step by step movement of the drum when the drum is rotated; and means frictionally engaging the other head of the drum for controlling the momentum of the drum in its rotation during the step by step movement of the drum.

13. In an advertising display device, in combination, a rotatable drum; means for rotating the drum; a shaft rotated by said means for rotating and provided with a crank; a rocking arm linked with said crank; a spring pawl on said arm; projections on one of the heads of said drum and engaged by said pawl; a bracket at the end of the drum opposite to the head having the projections thereon; and a friction pad carried by said bracket and engaging the head of the drum opposite to the first mentioned head.

14. In combination, opposed upright brackets; a drum rotatably mounted thereon and comprising heads and sides connecting said heads provided with rows of characters perforated therein; lamps in the drum; a stub shaft rotatably mounted in one of said brackets provided with a large contact member provided with an arcuate contact face; a gear bracket; an insulating block mounted upon said gear bracket; a pair of separated contact brushes mounted on said block and adapted simultaneously to engage and disengage from the said contact face as the contact member rotates; conductors connecting said brushes and said lamps in series; and means operated from said stub shaft to rotate said drum step by step when said brushes are disengaged.

15. In combination, opposed upright brackets; a drum rotatably mounted thereon having heads and a plurality of sides, each side having a row of openings therein; lamps in the drum; a motor bracket adjacent to one of said upright brackets; a motor on the

motor bracket and provided with a beveled gear on the lower end of its shaft; a governor shaft mounted in said motor bracket carrying a governor, a worm, and a beveled pinion engaged with said beveled gear; a reducing gear bracket adjacent to the other of the upright brackets; a drive shaft mounted in said motor and reducing gear brackets and provided at one end with a worm wheel engaging 5 said worm and at the other end with a small pinion; a rotary stub shaft mounted in said reducing gear bracket provided with a contact gear having a contact face and meshing with said small pinion; a pair of brushes 10 adapted to be simultaneously engaged by said face; means for electrically connecting said brushes and said lamps; and means operated from said shaft to rotate said drum.

16. In combination, a rotary drum having 20 a plurality of removable sides each provided with a row of openings therein; character frames removably seated in said openings; sources of light in said drum for cooperating with said openings in the sides of the drum; 25 means for rotating the drum step by step; and means for darkening said sources of light during step by step rotation of the drum.

17. In combination, a rotary drum having 30 a plurality of sides each provided with a row of openings therein, character frames removably seated in said openings; electric lamps in said drum for cooperating with said openings in the sides of the drum; means for supplying electricity to said lamps; means for 35 rotating the drum step by step; said means including a gear wheel having an electric contact face and means including contact brushes cooperating with said face for darkening 40 said lamps during step by step rotation of the drum.

18. In combination, a rotary drum having 45 heads and a plurality of removable sides connecting the heads, each side being provided with a row of openings therein; character frames receivable in said openings and having inwardly beveled marginal portions; and means cooperating with said marginal por-

tions for removably securing said frames in 50 said openings of the sides of the drum.

19. In combination, a rotary drum having 55 heads and a plurality of removable sides connecting the heads, each side being provided with a row of openings therein; character frames receivable in said openings and having inwardly beveled marginal portions 60 provided with apertures therein and a projection, and a latch and a bail cooperating with said apertures and projection for removably securing said frames in said openings in the 65 sides of the drum.

20. In combination, a rotatable drum; means for rotating the drum; means comprising a pawl for providing step by step movement of the drum during rotation; an 65 electric lamp; brushes to light the lamp; a gear wheel having an electric contact member engageable with the brushes to light the lamp on the back stroke of the pawl while the drum is stationary and disengageable 70 from the brushes for extinguishing the lamp during the active stroke of the pawl and while the drum is moving; and means for operatively connecting the pawl and 75 gear wheel.

21. In combination, a rotatable drum; means for rotating the drum; display characters carried by the drum; means comprising a pawl for providing step by step movement of the drum during 80 rotation; an electric lamp for illuminating said characters; brushes to light the lamp; a gear wheel having an electric contact member engagable with the brushes to light the lamp on the back stroke of the pawl while 85 the drum is stationary and disengageable from the brushes for extinguishing the lamp during the active stroke of the pawl and while the drum is moving; and means for operatively connecting the pawl and gear 90 wheel.

Signed at New York, in the county of New York and State of New York, this 21st day of February A. D. 1924.

CHARLES D. WINTERS.
